UNITED STATES PATENT OFFICE

CARLYLE HALL, OF SEATTLE, WASHINGTON

DESIGN FOR AN EGG YOLK SEPARATOR

Application filed August 18, 1931. Serial No. 40,879. Term of patent 7 years.

To all whom it may concern:

Be it known that I, CARLYLE HALL, a citizen of the United States, residing at Seattle, in the county of King and State of Washington, have invented a new, original, and ornamental Design for Egg Yolk Separators, of which the following is a specification, reference being had to the accompanying drawing, forming part thereof.

The figure is a view in perspective of an egg yolk separator, showing my new design.

I claim:

The ornamental design for an egg yolk separator, as shown.

CARLYLE HALL.
